UNITED STATES PATENT OFFICE.

MORRIS KARP, OF PASSAIC, NEW JERSEY, ASSIGNOR TO PASSAIC METAL WARE COMPANY, OF PASSAIC, NEW JERSEY, A CORPORATION OF NEW JERSEY.

CONTAINER.

1,103,674.

Specification of Letters Patent.

Patented July 14, 1914.

Application filed November 14, 1913. Serial No. 800,910.

To all whom it may concern:

Be it known that I, MORRIS KARP, a citizen of the United States, and resident of Passaic, in the county of Passaic and State of New Jersey, have invented certain new and useful Improvements in Containers, of which the following is a specification.

My invention relates to improvements in containers, such as oil cans and the like, provided with spouts or nozzles, and the object of my invention is to provide a spout or nozzle so constructed that it may be pushed within the can when not in use or for transportation, and whereby the spout or nozzle may be caused to project from the can for use.

In carrying out my invention I provide a guide adapted to be attached to a container at its outlet or neck, and a spout or nozzle 20 adjustably fitted to said guide to move in or out relatively thereto, with means for securely fitting said guide to the container or its neck, means to prevent leakage around the spout or nozzle when it is pushed outwardly for use, and means to close over the spout and make a tight fit to prevent leakage when the spout is pushed inwardly.

My invention also comprises novel details of improvement and combinations of parts 30 that will be more fully hereinafter set forth and then pointed out in the claims.

Reference is to be had to the accompanying drawings forming part hereof, wherein,

Figure 1 is a partly sectional side view of 35 a container embodying my invention, showing the parts in position for shipment; Fig. 2 is a similar view of the upper portion of the container, illustrating the parts in position for use, and Fig. 3 is a section on the 40 line 3, 3, in Fig. 2.

In the accompanying drawings the numeral 1 indicates any suitable container, such as a tin can, shown provided with a neck 1^a having screw threads 1^b.

45 At 2 is a guide or support for an adjustable spout or nozzle 3, which guide or support 2 is shown adapted to be secured at or upon neck 1^a. The guide 2 is shown provided with a gasket or washer 4 fitting adjacent its outer edges upon neck 1^a. The parts 50 2 and 4 are secured together so that said guide will be supported by gasket 4. For this purpose the outer end of guide 2 is shown flanged at 2^a and provided with 55 several projections 2^b, the outer ends of

which are secured to gasket 4. For such purpose I have shown the extreme ends of projections 2^b as bent backwardly at 2^c, and driven into gasket 4. Over gasket 4 and guide 2 is a cap 5 having threads meshing 60 with the threads 1^b of neck 1^a, so that when guide 2 is passed through the neck into the container, and its gasket 4 rests upon neck 1^a, the cap 5, by being screwed firmly upon gasket 4, will force the latter against the end 65 of the neck and secure the parts firmly together, with guide 2 depending from the neck into the container. Cap 5 is provided with a centrally disposed opening 5^a within which the spout or nozzle 3 is adapted to 70 slide, and said spout is provided at its inner end with a washer 6, that is adapted to bear against the inner surface of cap 5, as in Fig. 2, to prevent leakage of liquid through the opening in cap 5 around the spout when the 75 parts are in the position shown in Fig. 2. The inner end of spout 3 is shown flanged outwardly at 3^a and washer 6 rests upon said flange.

At 7 is a suitable spring shown located 80 within guide 2, and bearing at its inner end against the inturned abutment portion 2^f of said guide, the outer end of said spring bearing against the flange of spout 3, whereby said spout may be pushed by said spring 85 through opening 5^a in cap 5 to cause the washer 6 to bear tightly against said cap.

Guide 2 may be in tubular form having an inlet opening 2^d at its lower end, and having one or more openings 2^e near its outer 90 end, such openings permitting liquid to flow into said guide from the container.

At 8 is a cap screw-threaded to fit over the threads 5^b of cap 5, and adapted, when so screwed into position, to push the spout 3 into its guide, as in Fig. 1. Cap 8 is shown provided with an internal gasket or washer 9 adapted to seal against cap 5, and shown provided with a centrally disposed opening 9^a whereby the outer end of spout 3 may engage said cap. The cap 5 is provided with an external projection 5^e, shown in the form of an annular rib, against which the gasket 9 may be forced when cap 8 is screwed upon cap 5.

100 To assemble the parts, the spout with its washer and the spring may be pushed into guide 2, and then the end portions 2^a of the guide are closed in, the washer 4 having been secured to said guide. The washer 4 may 105

then be inserted in cap 5, and the guide may be pushed through the neck of the container, and the cap 5 screwed tightly thereon to force gasket 4 tightly against the end of the neck. This arrangement provides a simple and efficient means to enable the container first to be charged with its contents, and then to enable the cap and the guide for the spout to be secured in place, without the necessity of soldering said parts together. After the parts have been assembled, as stated, they will assume the positions shown in Fig. 2, with the spout projecting outwardly from the neck, washer 6 forming a tight fit against cap 5 by reason of the pressure of spring 7 against the washer. The cap 8 may then be placed over the spout and pushed toward cap 5, thereby pushing the spout into the can, and said cap 8 may be screwed upon cap 5 to retain the parts in the position shown in Fig. 1, for transportation and storage. Spring 7 will keep spout 3 pushed against cap 8, and the gasket 9 will make a tight fit against cap 5, whereby leakage is prevented. When the container is to be used, the cap 8 is unscrewed from cap 5, and spring 7 will then push spout 3 outwardly, as in Fig. 2, enabling the container then to be used in the manner of an ordinary oil can having a spout, as by squeezing the flexible walls or bottom of the container.

My improvements are simple and cheap to manufacture, and provide convenient and efficient means for keeping the container closed when not in use, and afford convenient use of the can, as customary with oil cans of this class.

Having now described my invention what I claim is:—

40 1. The combination of a container, a cap, means to support the cap upon the container, a guide suspended from the cap and depending within the container, a spout movable within the guide and through openings in the container and cap, and a spring within the guide to retain said spout projected from the guide through said openings.

2. The combination of a container having an opening, an aperture cap fitted over said opening, a guide suspended from the cap and depending within the container through said opening, a spout movable in said guide and through the opening in said cap, the guide having an abutment, and a spring within the guide acting against the spout and abutment for normally retaining the spout projected through the guide and cap.

3. The combination of a guide, and means to attach the guide to a container comprising a cap fitted to and supporting the guide, a spout, the guide having an abutment at its inner portion, a spring within the guide bearing against the spout and abutment to retain the spout projected through the cap

and guide, and means to prevent leakage between the spout and cap.

4. The combination of a guide, and means to attach the guide to a container comprising a cap fitted over and supporting the guide, a spout, means to retain the spout projected through the cap and guide, and a washer encircling the spout to engage the cap to prevent leakage between the cap and spout, said washer being fitted to slide with the spout within said guide.

5. The combination of a guide, and means to attach the guide to a container comprising a cap fitted over the guide, a spout, means to retain the spout projected through the guide, said spout having a flange at its inner end, and a washer upon the spout coacting with said flange.

6. The combination of a guide, a gasket connected therewith to engage a container, an apertured cap receiving said gasket, a spout within the guide adapted to be projected through the opening in the cap, and means coacting with the guide to retain said spout projected through said opening.

7. The combination of a guide, a gasket connected therewith to engage a container, an apertured cap receiving said gasket, said guide being suspended from the cap, a spout within the guide adapted to be projected through the opening in the cap, means coacting with the guide to retain said spout projected through the opening in the cap, and means to prevent leakage between the cap and spout.

8. The combination of a guide, a gasket connected therewith to engage a container, an apertured cap receiving said gasket, a spout within the guide adapted to be projected through the opening in the cap, a spring within the guide operating against the latter and against the spout to retain said spout projected through said opening, and a washer upon the spout adapted to engage said cap to prevent leakage between the spout and cap.

9. The combination of a guide, a gasket connected therewith to engage a container, an apertured cap receiving said gasket, a spout within the guide adapted to be projected through the opening in the cap, means to retain said spout projected through said opening, and a washer upon the spout adapted to engage said cap to prevent leakage between the spout and cap.

10. The combination of a container having a neck, a cap to fit said neck, a guide extending into the cap, means to suspend the guide from the container, a spout within the guide, a spring coacting with the spout and guide to normally press the spout outwardly, and means to prevent leakage between the spout and cap.

11. The combination of a container having a neck, a cap to fit said neck, a guide ex-

- tending into the cap, means to suspend the guide from the container, a spout within the guide, a spring carried by and coacting with the spout and guide to normally press the spout outwardly, means to prevent leakage between the spout and cap, and a second cap fitted over the first named cap and spout adapted to push the latter into the guide.
- 10 12. The combination of a container having a threaded neck, a threaded cap to fit said neck, a guide extending into the cap, a gasket within the cap connected with the guide and adapted to coact with said neck, a spout within the guide, a spring coacting with the spout and guide to normally press the spout outwardly, and a washer upon the spout to engage the cap.
- 15 13. The combination of a container having a threaded neck, a threaded cap to fit said neck, a guide extending into the cap, a gasket within the cap connected with the guide and adapted to coact with said neck, a spout within the guide, a spring coacting with the spout and guide to normally press
- 20 the spout outwardly, a washer upon the spout to engage the cap, and a threaded cap adapted to fit on the first named cap to push the spout into the guide.
- 25 14. The combination of a container having a threaded neck, a threaded cap to fit said neck, a guide extending into the cap, a gasket within the cap connected with the guide and adapted to coact with said neck, a spout within the guide, a spring coacting with the spout and guide to normally press the spout outwardly, a washer upon the spout to engage the cap, and a threaded cap adapted to fit on the first named cap to push the spout into the guide, the last named cap having an internal washer, the first named cap having a raised portion to coact with said washer.

Signed at Passaic, in the county of Passaic, and State of New Jersey, this 27th day of October, A. D. 1913.
